UNITED STATES PATENT OFFICE.

M. AMBROSE METZGER AND FRANK SCHILLING, OF LAFAYETTE, INDIANA.

HAND-TRUCK.

SPECIFICATION forming part of Letters Patent No. 303,657, dated August 19, 1884.

Application filed January 22, 1884. (No model.)

To all whom it may concern:

Be it known that we, MARION A. METZGER and FRANK SCHILLING, of Lafayette, in the county of Tippecanoe and State of Indiana, have 5 invented certain Improvements in Trucks, of which the following is a specification.

Our invention relates to trucks for handling casks; and it consists in certain improvements whereby the truck is adapted to facilitate 10 placing casks upon a rack or raised platform. The construction is particularly designed with reference to casks tapped at the end, as presently explained.

In the drawings, Figure 1 is a perspective view of my improved truck with a cask upon it ready to be moved to any desired point; Fig. 2, a perspective view of the same as made ready for setting the cask upon its rack; Fig. 3, a side elevation showing the said operation; 20 Fig. 4, a perspective view of the truck; Figs. 5 and 6, perspective views illustrating certain modifications.

Molasses hogsheads and casks containing similar thick fluids are usually tapped at the 25 side, and as a consequence a considerable quantity of such material remains in the cask and cannot be drawn off, being below the faucet or gate. It is therefore desirable to tap the hogshead or cask at the end; but as this must be 30 done before the cask is placed upon the rack, and the gate or faucet projects below the lower end of the cask when the latter is upon the rack, it will be seen that much difficulty would be encountered in placing the cask upon the 35 rack unless special means for that purpose were provided. To obviate such difficulty constitutes then the main object of this invention, which will now be explained in connection with the drawings, in which—

40 A indicates a truck-frame composed of side bars, *a*, and cross-braces *b*, provided with a scoop, *B*, and *C* the wheels upon which said frame is carried. The side bars, *a*, instead of being carried back the usual distance, are 45 made somewhat shorter than common, and are furnished at their rear ends with strong hooks *c*. On the inner sides of the side bars are hooks *D*, Figs. 1 and 4, formed of cylindrical iron rods bent into suitable shape, and carried in eyes or staples *d*, which permit both a 50 lateral and a longitudinal motion of the hooks

to adapt them to casks of different diameters and lengths, the office of said hooks being to engage over the chines of a cask to draw the same over upon the truck after the scoop has 55 been passed under the lower end of the cask.

Applied to the side bars, *a*, in any suitable or convenient manner are handles *E*, which may be made to project beyond either end of the side bars, or brought wholly within such 60 end, as desired. When the truck is to be used in its ordinary capacity, the handles are made to extend beyond the rear ends of the side bars, *a*, as in Figs. 1 and 4; but when the cask has been carried to the desired point, the handles are 65 brought within the length of the side bars, *a*, at the rear and extended at the forward end beyond the scoop *B*, as shown in Figs. 2 and 3. This leaves the hooks *c* projecting beyond the rear end of the truck, so as to engage with 70 staples or with a rod, *e*, at the front edge of the rack or platform *F*, as in said figures. By then lifting or raising the handles *E* the cask may be readily set over upon the rack.

In order that the cask may not fall away 75 from the truck and injure the faucet *G* or other outlet device, the scoop *B* is perforated or otherwise adapted to receive a detachable claw or hook, *H*, which is hooked or engaged over the end of the cask when the same is 80 fully upon the truck, as in Fig. 2. This claw is of course removed except during the operation mentioned; and may obviously be attached to the side bars instead of the scoop.

Referring again to Figs. 1, 2, and 3, a convenient arrangement of the handles will be seen. The side rails, *a*, are provided with guides or metal loops *f*, in which are mounted longitudinally-movable bars *g*, having handles *E* formed at both ends. When the handles are 85 required at the rear, the bars are pushed or drawn back and locked, as in Figs. 1 and 4. When wanted at the front end, they are moved in the opposite direction and locked forward, as in Figs. 3 and 4. For the purpose of thus locking the handles in either position required, we provide a gravitating cross rod or bar *I*, which has its ends bent up against the outer faces of the side bars, *a*, and carried in eyes or staples *h* secured to said bars. The side bars, *a*, and 90 the handle-bars *g* are both recessed sufficiently to permit the cross-bar *I* to enter its whole

thickness or depth into the faces of either, so that it may be drawn up into the recess *i* of the side bars, clear of the handle-bars, thus allowing them to be moved longitudinally, or 5 dropped into the forward notches, *k*, or rear notches, *j*, of the handle-bars, to hold them in whichever position may be required. While this forms a very simple and compact arrangement, we do not desire to limit ourselves 10 thereto, but may adopt any equivalent construction, many of which will readily suggest themselves to the skilled mechanic. For instance, the handle-bars may be at the sides instead of beneath the side bars, *a*, or they may 15 be hinged or jointed to the side bars midway between the ends of the latter, as in Fig. 5, and arranged to swing at either end, suitable hooks or projecting arms being provided to prevent the rise or fall of the handles independently of the body of the truck. Another 20 convenient construction is shown in Fig. 6, in which four independent handles *E* are represented as arranged to fold against the sides of the frame *A*, each adapted to be turned outward, as required, to the positions indicated 25 in dotted lines in said figure.

A spring, *J*, may be arranged to bear against the flat faces of handles *E*, as in Fig. 6, and to hold said handles either in their inner or outer 30 positions, in the same manner, essentially, as a knife-blade is held by its spring.

Having thus described our invention, what we claim is—

1. In a truck, the combination of a wheeled

frame, *A*, provided with a scoop, *B*, at one 35 end, and hooks *c* at the opposite end, and handles *E*, adapted to be extended from or brought within either end, substantially as set forth.

2. In combination with a truck having a 40 wheeled frame, provided at one end with a scoop, and at the other end with hooks, substantially such as described and shown, handles adapted to be extended at will from either end of the frame, and a claw or hook, *H*, attached to the scoop or front part of the truck, for the purpose explained. 45

3. In combination with a truck having hooks at its rear end, substantially as set forth, a claw, *H*, detachably connected with the forward end of the truck, substantially as and 50 for the purpose explained.

4. The herein-described truck, consisting of frame *A*, provided with scoop *B* at the forward end, and hooks *c* at the rear end, wheels, 55 longitudinally-movable bars *g*, provided with notches *j* *k*, and gravitating cross-bar *I*.

5. In combination with wheeled frame *A*, provided with scoop *B* and hooks *c* at its opposite ends, extensible handles *E*, and hooks 60 *D*, adapted to move longitudinally and laterally, substantially as set forth.

M. AMBROSE METZGER.
FRANK SCHILLING.
